(57) CLAIM

The ornamental design for a cosmetic mat with customized pockets, as shown and described.

DESCRIPTION

FIG. 1 is a perspective view of a first embodiment of a cosmetic mat with customized pockets showing my new design.

FIG. 2 is a top view thereof.

FIG. 3 is a bottom view thereof.

FIG. 4 is a perspective view of an alternate embodiment of my new design.

FIG. 5 is a top view thereof; and,

FIG. 6 is a bottom view thereof.

The broken lines depicted unclaimed portions of the cosmetic mat and form no part of the claimed design.
